UNITED STATES PATENT OFFICE.

ADOLPH WILLIAM HOLL, OF CLEVELAND, OHIO, ASSIGNOR TO GEORGE W. BOWEN, OF AUBURN, NEW YORK.

GREASE-CUP.

1,213,372.

Specification of Letters Patent. Patented Jan. 23, 1917.

Application filed April 29, 1915. Serial No. 24,676.

To all whom it may concern:

Be it known that I, ADOLPH WILLIAM HOLL, a citizen of the United States, residing at Cleveland, in the county of Cuyahoga and State of Ohio, have invented a certain new and useful Grease-Cup, of which the following is a specification:

This invention relates to grease cups having rotatable caps, and has for its object a particularly simple and efficient construction whereby the rotatable cap is held from unintentional turning; and the invention consists in the combinations and constructions hereinafter set forth and claimed.

In describing this invention, reference is had to the accompanying drawings, in which like characters designate corresponding parts in all the views.

Figure 1 is a longitudinal sectional view, partly in elevation, of a grease cup embodying my invention, the cover being shown as partly out of its final position. Fig. 2 is a fragmentary sectional view of the upper part of the grease cup showing the cover as in its final position when said parts are completely assembled.

This grease cup comprises, generally, a base having a barrel portion, a cover including inner and outer cap members having perforations therethrough, the inner cap member being secured to the base and the outer cap member being rotatably mounted on the inner cap and being rotatable to bring its perforation into and out of registration with the perforation of the inner cap member, means for holding the cap members from separation, and friction means for holding the outer cap member from unintentional turning.

1 designates the base of the grease cup, which is here shown as formed with a barrel portion 2, and a funnel-shaped part 3 depending from the barrel portion 2 and terminating in a hollow threaded stem or nipple 4, by means of which the base is connected to the part to be lubricated. The base here shown is also formed with a central tube 5 extending into the stem or nipple and in which is located a wick 6 by means of 50 which the grease is conveyed from the base to the part to be lubricated.

7 and 8 designate, respectively, the inner and outer cap members forming the cover, said cap members having dome shaped tops

9, 10 engaging each other, and annular side walls 11, 12 spaced apart from each other. The wall 11 of the inner cap member projects beyond the edge of the annular wall of the outer cap member and snugly fits within the upper end of the barrel 2, and the wall 12 of the outer cap member loosely fits or laps over the upper end of the barrel 2. The wall 12 is also knurled for facilitating the turning thereof. The tops 9, 10 are formed with perforations 13, 14 arranged to be brought into and out of alignment during turning of the outer cap member 8, in order that grease may be inserted into the cup and the perforations closed after the cup is filled. The cap members are held from separation by a centrally located pin or rivet 15 having inner and outer heads, the pin serving as a pivot about which the outer cap member 8 rotates. The friction means for holding the cap member 8 from unintentional turning is interposed between the annular walls of the cap members 7, 8 and between the upper edge of the barrel portion of the base and the top 10 of the outer cap member 8. Said means comprises a spring 16 encircling the wall 11 of the inner cap member and located in the space between the annular walls 11, 12 of the inner and outer cap members. Said spring is a compression spring consisting of a single coil 85 normally having its opposite ends 17 deflected in opposite directions, as shown in Fig. 1, the spring being compressed into a plane as the cover is assembled onto the barrel 2, that is, as the inner cap member 7 is 90 pressed into the barrel 2, as shown in Fig. 2. Hence, the ends of the spring tend to press in opposite directions toward the upper edge of the barrel 2 and the opposing surface of the top of the outer cap member 8. Said 95 friction means also usually includes a ring shaped shoe 18 interposed between the spring 16 and the top of the outer cap member 8. The inner cap member is constructed to snugly fit within the barrel 2 so that when 100 the parts are assembled, the cover is permanently in position. In forming the grease cup, the cap members 7, 8 are assembled and the shoe 18 and spring 16 placed around the annular wall 11 of the inner cap member 105 and the advance edge of the wall 11 inserted in the upper end of the base 1, as seen in Fig. 1. The cover is then pressed to-

ward the base to shove the wall 11 of the inner cap member into the base, as seen in Fig. 2.

What I claim, is:—

- 5 1. A grease cup comprising a base, a cover including inner and outer cap members having perforations, the inner cap member being secured to the base, the outer cap member being rotatably mounted on the inner cap member and having its perforation arranged to be brought into and out of alignment with the perforation in the inner cap member during the rotation of said outer cap member, and the outer cap member and the base having opposing surfaces, and means interposed between the opposing surfaces of the outer cap member and the base and acting to retard turning of the outer cap member, substantially as and for the purpose specified.

- 10 2. A grease cup comprising a base having an annular wall, a cover for the base including inner and outer cap members, the inner cap member having an annular wall fitting into the upper end of the annular wall of the base, and the outer cap member being rotatably mounted on the inner cap member and having an annular wall lapping the outer face of the base, and friction means interposed between the annular walls of the cap members, and also between the upper edge of the annular wall of the base and the top of the outer cap member, said means acting as a brake on the outer cap member to prevent turning thereof, substantially as and for the purpose set forth.

- 15 3. A grease cup comprising a base having a barrel portion, and a cover including inner and outer cap members having their tops engaging each other and their sides lapping respectively the inner and outer faces of the barrel portion of the base, the cap members being formed with perforations in their tops, and the outer cap member being rotatable relatively to the inner cap member and the base for bringing the perforation in its top into and out of registration with the perforation of the inner cap member, substantially as and for the purpose described.

- 20 4. A grease cup comprising a base having a barrel portion, a cover including inner and outer cap members having their tops engaging each other, and their sides lapping respectively the inner and outer faces of the barrel portion of the base, the cap members being formed with perforations in their tops, and the outer member being rotatable relatively to the inner cap member and the base for bringing the perforation in its top into and out of registration with the perforation of the inner cap member, and friction means interposed between the sides of the cap members and between the top of the outer cap member and the opposing sur-

face of the barrel portion of the base, substantially as and for the purpose described.

5 5. A grease cup comprising a base, a cover including inner and outer cap members having perforations, the inner cap member being secured to the base, the outer cap member being rotatably mounted on the inner cap member and having its perforation arranged to be brought into and out of alignment with the perforation in the inner cap member, and the outer cap member and the base having opposing surfaces, and means interposed between the opposing surfaces of the outer cap member and the base and acting to retard turning of the outer member of the cover, said means including an annular compression spring, substantially as and for the purpose set forth.

10 6. A grease cup comprising a base having an annular wall, a cover for the base including inner and outer cap members, the inner cap member having an annular wall fitting into the upper end of the annular wall of the base, and the outer cap member being rotatably mounted on the inner cap member and having an annular wall lapping the outer face of the annular wall of the base, and friction means interposed between the annular walls of the cap members, and also between the upper edge of the annular wall of the base and the top of the outer cap member, said means acting as a brake on the outer cap member to prevent turning thereof, and including an annular compression spring encircling the annular wall of the inner cap member, substantially as and for the purpose described.

15 7. A grease cup comprising a base, a cover including inner and outer cap members having perforations, the inner cap member being secured to the base, and the outer cap member being rotatably mounted on the inner cap member and having its perforation arranged to be brought into and out of alignment with the perforation of the inner cap member during the rotation of said outer cap member, and a spring pressed shoe acting against the outer cap member, substantially as and for the purpose specified.

20 8. A grease cup comprising a base having an annular wall, a cover for the base including inner and outer cap members, the inner cap member having an annular wall fitting into the upper end of the annular wall of the base, and the outer cap member being rotatably mounted on the inner cap member and having an annular wall lapping the outer face of the annular wall of the base, and friction means interposed between the annular walls of the cap members, and also between the upper edge of the annular wall of the base and the top of the outer cap member, said means including an annular compression spring encircling the

annular wall of the inner cap member, and a shoe pressed by the spring against the inner face of the top of the outer cap member, substantially as and for the purpose set forth.

9. A grease cup comprising a base having a barrel portion, a cover including inner and outer cap members having their tops engaging each other, and having their annular sideslapping respectively the inner and outer faces of the barrel portion of the base, the cap members being formed with perforations in their tops, the annular side of the inner cap member snugly fitting the upper end of the barrel portion of the base and the outer cap member being rotatable relatively to the inner cap member and the base for bringing the perforation in its top into and out of registration with the perforation of the inner cap member, and a compression spring consisting of a single coil encircling the annular side of the inner cap member and being interposed between the annular side thereof and the annular side wall of the outer cap member and having its ends deflected in opposite directions, said ends being compressed into a plane during the placing of the inner cap member in position whereby said ends press in opposite directions toward opposing surfaces of the base and the outer cap member, substantially as and for the purpose described.

10. A grease cup comprising a base and a cover including inner and outer cap members having perforations, the inner cap

member having a cylindrical wall snugly fitted to a cylindrical wall of the base and the outer cap member being rotatably mounted on the inner cap member, and means located centrally of the cap members for holding the cap members from separation, substantially as and for the purpose set forth.

11. A grease cup comprising a base having an annular wall, a cover for the base including inner and outer cap members, the inner cap member having an annular wall fitting into the upper end of the annular wall of the base, and the outer cap member being rotatably mounted on the inner cap member and having an annular walllapping the outer face of the base, friction means interposed between the annular walls of the cap members, and also between the upper edge of the base and the opposing top of the outer cap member, said means acting as a brake on the outer cap member to prevent turning thereof, and means located centrally of the cap members for holding the cap members from separation, substantially as and for the purpose set forth.

In testimony whereof, I have hereunto signed my name in the presence of two attesting witnesses, at Cleveland, in the county of Cuyahoga, and State of Ohio, this 6th day of February, 1915.

ADOLPH WILLIAM HOLL.
